OF FIG. 4.

UNITED STATES PATENT OFFICE.

CHARLES S. PRICE, OF BETHLEHEM, PENNSYLVANIA, ASSIGNOR TO SPLITDORF-BETHLEHEM ELECTRICAL COMPANY, OF BETHLEHEM, PENNSYLVANIA, A CORPORATION OF NEW JERSEY.

AUTOMOBILE RADIATOR CAP.

Application filed June 10, 1924. Serial No. 719,026.

My invention consists of a novel design and construction in radiator caps for motor vehicles, whereby a closure for the filling aperture in such radiators is produced which is of greater simplicity and general utility than the radiator caps heretofore used or known.

My invention further consists of a novel construction in radiator caps for motor vehicles, whereby the filling aperture may be opened and closed expeditiously without any of the inconveniences incidental to these operations on the radiator caps now in use.

My invention consists particularly of certain novel constructions in radiator caps, including a hinged lid and a hinged clasp or locking member therefor, adapted to draw the lid into the closed position and positively lock the same thereafter by a simple lateral pressure thereon of the thumb of the operator; and when in a locked position said locking member is adapted to present a front vertical ornamental face adapted to carry a shield or escutcheon having an initial or other symbol or emblem thereon, said locking member being of ornamental configuration and so constructed as to conceal its pivotal connection and the locking lug on said lid.

My invention further consists of certain other novel features of construction, whereby all the non-integral parts of the radiator cap are permanently and non-removably united and the body of the radiator cap is in turn secured to the radiator in a non-removable manner; so that the cap as a unit, as well as each part thereof is theft proof.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized, and that my invention is not limited to the precise arrangement and organization of the instrumentalities as herein shown and described.

Figure 1 represents a front elevation of a novel radiator cap embodying my invention.

Figure 2 represents a plan view of the same.

Figure 3 represents a section on line 3—3 of Figure 2.

Figure 4 represents a side elevation of the radiator cap showing the lid in closed position.

Figure 5 represents a side elevation of the radiator cap with the lid in open position.

Figure 6 represents a section on line 6—6 of Figure 1.

Figure 7 represents a section similar to Figure 6 showing the lid in open position.

Figure 8 represents a plan view of the underside of the lid.

Figure 9 represents a section on line 9—9 of Figure 4.

Similar numerals of reference indicate corresponding parts in the figures.

Referring to the drawings:—1 designates the body of the cap, of cylindrical or sleeve shape, and having the two handles or arms 2 on the respective sides of the body portion 1, and integral therewith.

The cylindrical body is threaded at the lower portion thereof to engage a similarly threaded pipe and this thread may be internal as shown at 3 or external (not shown) depending upon the thread on the radiator inlet pipe.

In two diametrically opposed portions namely the front and rear of the upper edge of the body 1, there are formed bifurcated hinge lugs 4 and 5 respectively integral with the body portion and having recesses 6 and 7 between said lugs.

Hinged to the front lugs 4 and rear lugs 5 are the locking member with its thumb piece 8 and the cover or lid 9 respectively; each having a hinge member or tongue 10 and 10 respectively adapted to fit in the respective recesses 6 and 7 of the said lugs 4 and 5. The bearing apertures for the horizontal hinge pivots or pins 11 do not pass completely through the hinge lugs but terminate within one of the lugs as shown at 12 in Figure 9. By this means the pivot pins 11 after being driven into place cannot be removed once their outer ends are cut flush with the body of the cap as shown at 13, and hence the pins secure the lid as well as the locking and thumb piece to the body of the radiator caps in a non-removable or theft proof manner.

The locking member 8 is provided with the

recess 14, the upper wall 15 of which is inclined upwardly and inwardly. Upon the periphery of the lid at a point in alignment with the recess 14, I provide the projecting locking lug 16 formed integral with the lid and having its nose 16^x rounded and its upper surface 17^x inclined rearwardly and downwardly to coact and interlock with the upper wall 15 of the locking member 8, said lug 16 being of a thickness and depth to be readily contained within the recess 14 when the parts are interlocked as seen in Figure 6. In the lower face of the lid I provide a circular gasket retaining groove 17 of substantially semi-circular cross section concentric with the lid and of such diameter that the center of the groove will coincide with the inner edge of the upper face of the radiator cap body when the lid is in the closed position. In this groove 17 is placed an elastic rubber gasket 18 of suitable cross section so that a portion thereof will extend out of the groove beyond the lower face of the lid.

In closing the radiator cap it is only necessary to bear down lightly on the lid and then press upon the thumb piece of the locking member 8 to force it against the lug 16 with a lateral thrust of the thumb thereon, as indicated by the arrows *a* and *b* in Figure 7. The wedging action produced by the wall 15 riding over the nose and the outer incline of the lug 16 forces the lid down tight against the compression of the gasket 18 which is then compressed and bears against the inner edge of the body 1. When the wall 15 rides over the top of the nose 16 it naturally is forced over the inner incline 17^x of the lug 16 into locked position, as shown in Figure 6, so that it can be unlocked only by a similar thrust of the thumb in the opposite direction as indicated by the arrow *c* in Figure 6.

The thumb piece is provided with a front wall 19 of any ornamental contour such as that shown in Figure 1 which stands vertical when the parts are locked and may be further provided with a peripheral bead 20 for retaining in position any ornamented plate or sheet of metal 21 such as shown in Figure 1, bearing thereon any monogram, initials, insignia or coat of arms. The plate 21 in addition to being retained in position by the raised border 20, is also secured by means of rivets or screws 22. In order to permanently lock the body 1 of the radiator cap to the radiator of the automobile, I provide a vertical threaded hole 23 in the body of the cap and in line with the main thread 3, into which hole I insert a locking screw (not shown in the drawings).

I desire to call especial attention to the novel construction and function of the locking member 8, which is on the front of the cap and is so constructed and positioned that when it is open as seen in Figures 5 and 8, it

falls forward by gravity and its rear portion clears the front end of the lug 16. The front wall 20 which serves as a thumb pressure piece is inclined and located at the front of the cap and radiator where it is readily accessible to the operator standing in front of the radiator to fill the same, and there is no necessity for reaching over to the rear of the cap or cover to manipulate the same.

When the cover is locked the thumb piece 75 or locking member stands vertical as seen in Figures 4 and 6, and the cap is closed steam and water tight, it being apparent that said locking member is of ornamental configuration and that when in its locked or vertical 80 position, it serves effectively to conceal its pivotal connection and the locking lug on the cap. When it is desired to unlock the cover this can be readily done by pressing on the rear inclined wall 24, the locking member 8 85 then moving from the position seen in Figure 6, to the position seen in Figure 7, and the cover 9 moving automatically to a slight open position, as seen in said Figure 7. The outer walls of the locking member 8 enter 90 the recesses 25, seen in Figure 8, when the cover is locked and thus impart a neat and finished appearance to the front of the cap.

It is thus seen that my novel automobile 95 radiator cap possesses a number of distinct advantages over automobile radiator caps heretofore in use, namely, the hinged lid and its lock provide a simple and yet very effective closure for the filling opening, with the use of a minimum number of parts; enables an easy mode of operation, secures the lid to the body in a water tight manner and at the same time positively locking the same 100 against any tendency to open up due to the jarring and vibration of the automobile. 105

My novel construction further provides an automobile radiator cap which as a unit, as well as in every part thereof is theft 110 proof, and a locking means for said cap of two fold utility, namely it serves to lock the lid and provides an ornamental effect.

Having thus described my invention what I claim as new and desire to secure by Letters Patent, is:—

1. A radiator cap for motor vehicles, comprising a tubular body, having a rear recess therein, a lid having a rear hinge member pivotally mounted in said rear recess, and provided at its bottom with an annular gasket receiving groove, a gasket in said groove adapted to cause said lid to be slightly raised from its seat when unlocked, a locking lug projecting from the front of said lid and having its upper surface rearwardly and downwardly inclined, and a front locking member having a lower offset hinge member pivoted in a recess in the front of said body below the top thereof and provided with a rearwardly extending upper lug having its bottom wall substantially conforming to the 130

top of the front locking lug of said lid, the pivotal point of said front locking member being inside of its center of gravity so that normally when unlocked it gravitates outwardly away from said lid, said locking member being of ornamental configuration and serving to conceal its pivotal connection and the locking lug on said lid.

2. A radiator cap for motor vehicles comprising a tubular body, having a rear recess therein below its top, a lid having a rear pendant hinge member pivotally mounted in said rear recess, and provided at its bottom with an annular gasket receiving a groove, a gasket in said groove adapted to cause said lid to be slightly raised from its seat when unlocked, a locking lug projecting from the front of said lid and having its upper surface rearwardly and downwardly in-

clined, and a front locking member having a lower offset hinge member pivoted in a recess in the front of said body below the top thereof and provided with a rearwardly extending upper lug having its bottom wall substantially conforming to the top of the front locking lug of said lid, the pivotal point of said front locking member being inside of its center of gravity so that normally when unlocked it gravitates outwardly away from said lid, said locking member having its front wall adapted to stand vertically when locked and being of ornamental configuration and serving to conceal its pivotal connection and the lug on said lid and provided with a rearwardly inclined top wall to facilitate unlocking.

CHARLES S. PRICE.
